COMBINATION LETTER OPENER AND NAIL CLEANER

Stanley W. Wathon, Woodside, N. Y.

Application August 10, 1949, Serial No. 4,388

Term of patent 14 years

(Cl. D74—1)

To all whom it may concern:

Be it known that I, Stanley W. Wathon, a citizen of the United States, residing at Woodside, in the county of Queens and State of New York, have invented a new, original, and ornamental Design for a Combination Letter-Opener and Nail-Cleaner, of which the following is a specification, reference being had to the accompanying drawing, forming part thereof.

In the drawing:

Fig. 1 is a front elevational view of a combination letter-opener and nail-cleaner, showing my new design;

Fig. 2 is a side view thereof, and

Fig. 3 is a rear view of the disclosure in Fig. 1.

I claim:

The ornamental design for a combination letter-opener and nail-cleaner, substantially as shown.

STANLEY W. WATHON.
